Wyatt, P.C.

(57)

CLAIMI claim the ornamental design for a shoe, as shown and described.DESCRIPTIONFIG. 1 is a front perspective view of a shoe, showing my new design;

FIG. 2 is a right side view thereof; and,

FIG. 3 is a rear perspective view thereof.

The dot-dot-dash broken lines adjacent to the shaded area represents unclaimed boundaries of the claimed design.
The broken lines depicting the remainder of the shoe show features that form no part of the claimed design.1 Claim, 3 Drawing Sheets(56)
